MATTRESS OR CUSHION

Filed April 2, 1928

INVENTOR.
Walter F. Roeske,
BY *Sam O'Sherry*,
his ATTORNEY.

Patented Aug. 27, 1929.

UNITED STATES PATENT OFFICE.

WALTER F. BOESKE, OF CHICAGO, ILLINOIS.

MATTRESS OR CUSHION.

Application filed April 2, 1928. Serial No. 286,509.

This invention relates to mattresses or cushions, and its principal object is to provide a simple, durable and comparatively inexpensive spring construction for mattresses and cushions which can be constructed and assembled with great rapidity and at considerably less cost than the ordinary spring constructions for mattresses and cushions.

10 Another object is to minimize the amount of material employed in the connecting means between the coiled springs and the covering material to which the springs are attached. Another object is to provide improved non-metallic means whereby the end coils or convolutions of the springs may be quickly and readily attached to the covering material for the springs. Another object is to provide a plurality of layers of fabric between the middle coils and end coils of the springs and without increasing the minimum amount of material required for connecting the springs to the covering material, whereby a more durable mattress or cushion is obtained.

With these and other objects and advantages in view, this invention consists in the several novel features of construction, arrangement and combination of parts hereinafter fully set forth and claimed.

30 The invention is clearly illustrated in the drawing accompanying this specification in which—

Figure 1 is a fragmental vertical cross section taken through a mattress or cushion spring construction, and illustrating a simple embodiment of the present invention;

Fig. 2 is a perspective view of a fragment of one of the covers of the spring construction, and showing the spring retaining strips secured thereto;

Fig. 3 is an enlarged fragmental perspective view showing, in detail, the connection between the retainer strips and covering material;

Fig. 4 is a fragmental horizontal section taken on the line 4—4 of Fig. 1; and

Fig. 5 is a fragmental plan of the mattress or cushion spring construction.

50 Referring to said drawing, which illustrates a single embodiment of the present invention applied to a mattress or cushion, the reference characters 6, 6 designate two pieces of covering material which enclose the springs, and said pieces may be of the desired size and shape to form a spring con-

struction of desired dimension. Between the two pieces of covering material are the coiled springs 7, the end coils of which are connected to the covering material by cross-wise laid or intersecting strips of fabric material 8 stitched to the covering material.

55 In order to obtain the best results, it is preferred to use coiled springs of that type in which the end coils are of a greater diameter than the intermediate ones, such a type of spring being shown in the drawing. The strips of fabric material 8 are stitched to the inner sides of the covering material 6 by rows of stitches 9 that run transversely of the strips through which they pass and run parallel with and approximately midway between the other strips.

There are two layers of strips, the strips of one layer extending parallel with each other and running in one direction, and the strips of the other layer extending parallel with each other and running in a direction at right angles to the strips of the first mentioned layer. The strips of each layer are spaced apart (center to center) a distance approximately equal to the diameter of the end coils of the springs, and the rows of stitches are spaced apart a distance approximately equal to or slightly greater than the diameter of the end coils of the springs.

60 The covering material and intersecting parts of the strips bounded by the adjacent rows of stitches, form square pockets having open corners into which the end coils 10 of the springs are inserted, and the four closed portions of the sides of said pockets confine the end coils of the springs against displacement with respect to the covering material and locate the springs in proper position 65 relative to each other throughout the extent of the spring construction. In attaching the coiled springs to the covering material, the end coil of a spring is inserted between two intersecting parts of the strips and the covering material and turned upon its axis until the whole or greater part of the end coil is brought between the strips and covering material. Both ends of the springs are attached to the covering material in the same manner, 70 after which the sides and ends of the spring construction are closed in the usual manner, and the usual cotton, felt, or the like, placed around it and covered with the usual outer covering material, as is well understood by 75 those skilled in the art to which this invention pertains.

It is apparent that a much simpler, neater and more efficient spring construction is obtained with the use of the intersecting strips of material attached to the covering material as described, than any construction where layers of stitched together material are used in which slits are formed in one of the layers through which the end coils of the springs are inserted.

10 Furthermore, the intersecting portions of the strips provide two layers of material between the middle coils and end coils of the springs, thereby greatly increasing the efficiency of the mattress or cushion. When 15 the spring is compressed, in use, the middle coils are pressed against the intersecting strips, and because of the double thickness of material between the middle coils and end coils, the life of the mattress or cushion is 20 lengthened. This is particularly noticeable in mattress or cushions having springs of which the diameter of the coils decreases toward the middle of the spring. The intersecting strips, together with the covering, 25 provides three layers which fully resist the tendency for the springs to push through the material. Furthermore, since the strips are whole throughout their extent, the tendency to fray out at slit places is eliminated, 30 and, consequently, they last longer than a slit layer of material.

Furthermore, the machinery for making the slits, and the time and labor required in making them is eliminated, and, consequently, the cost of production is reduced 35 considerably. Furthermore, a saving is had because the strips may be formed of material that would otherwise be waste material. Also, by reason of the open corner construction 40 of the pockets, the insertion of the end coils of the coiled springs is facilitated, because the workman is able to observe the end coil as it is turned around in the pocket.

More or less variation of the exact details 45 of construction is possible without departing from the spirit of this invention. I desire, therefore, not to limit myself to the exact form of the construction shown and described, but intend, in the following 50 claims, to point out all of the invention disclosed herein.

I claim as new, and desire to secure by Letters Patent:

55 1. In a spring construction, the combination of a fabric covering, intersecting fabric strips lying in planes substantially parallel with and secured to said fabric covering by rows of fastening means running crosswise through each strip at places between the intersections of the strips, whereby open cornered pockets are formed and coiled springs having open-ended coils confined in the pockets between intersecting strips and the fabric covering with the major portion of 60 said end coils covered by said intersecting strips, the extent of said corner openings being less than that of the end coils, whereby displacement of the end coils through the corner openings is prevented.

65 2. In a spring construction, the combination of a fabric covering, intersecting fabric strips lying in planes substantially parallel with and secured to said fabric covering by rows of fastening means running crosswise through each strip at places between the intersections of the strips, whereby open cornered pockets are formed and coiled springs having open-ended coils confined in the pockets between intersecting strips and the fabric covering with the major portion of said end coils covered by said intersecting strips, the extent of said corner openings being less than that of the end coils, whereby displacement of the end coils through the corner openings is prevented.

strips, the extent of said corner openings being less than that of the end coils, whereby displacement of the end coils through the corner openings is prevented.

2. In a spring construction, the combination of a fabric covering, intersecting fabric strips lying in planes substantially parallel with and secured to said fabric covering by rows of fastening means running crosswise through each strip at places between the intersections of the strips, whereby open cornered pockets are formed and coiled springs having open-ended coils confined in the pockets between the intersections of the strips, the extent of said corner openings being less than that of the end coils, whereby displacement of the end coils through the corner openings is prevented.

3. In a spring construction, the combination of a fabric covering, intersecting fabric strips lying in planes substantially parallel with and secured to said fabric covering by rows of fastening means running crosswise through each strip at places between the intersections of the strips, whereby open cornered pockets are formed and coiled springs having open-ended coils confined in the pockets between the intersections of the strips, the extent of said corner openings being less than that of the end coils, whereby displacement of the end coils through the corner openings is prevented.

4. In a spring construction, the combination of a fabric covering, a layer of spaced fabric strips extending along the covering in one direction, and a layer of spaced strips laid crosswise of the strips of the first layer and extending along the covering, rows of fastening means extending approximately midway between the parallel strips and passing through the strips which intersect them, whereby open cornered pockets are formed between the intersecting strips and covering, and coiled springs having their end coils held in said pockets with the major portion of said end coils covered by said intersecting strips, the extent of said corner openings being less than that of the end coils, whereby displacement of the end coils through the corner openings is prevented.

5. In a spring construction, the combination of two spaced fabric coverings, each having intersecting fabric strips lying in planes substantially parallel therewith on the face opposed to the other covering, said strips being stitched to their associated covering by

stitches running approximately midway between the parallel strips and through the strips which intersect them and thereby form open cornered pockets, and coiled springs extending between said coverings and having their end coils held in the pockets between the intersecting parts of the strips and the associated covering with the major portion of said end coils covered by said intersecting strips, the extent of said corner openings being less than that of the end coils, whereby displacement of the end coils through the corner openings is prevented. ¹⁰
